UNITED STATES PATENT OFFICE.

JOSEPH H. DORVAL, OF BELFIELD, NORTH DAKOTA.

LEATHER-WORKING TOOL.

Application filed December 20, 1927. Serial No. 241,360.

The present invention relates to improvements in tools and has reference more particularly to an implement that is adapted to be used in cutting strips of leather of various widths in a simple and efficient manner.

Another important object of the invention is to provide a tool of the above mentioned character wherein means is provided for creasing the strip of leather, additional means being associated with the tool whereby holes may be punched in the strip.

A further object of the invention is to provide a tool of the above mentioned character wherein the blade carrying gage bar may be adjusted to facilitate the cutting of strips of leather of any desired width, means being provided for securing the slidable gage bar in its adjusted position.

A still further object is to provide a tool of the above mentioned character which is simple in construction, inexpensive, strong and durable and further well adapted to the purpose for which it is designed.

Other objects and advantages of the invention will become apparent from the following description when taken in connection with the accompanying drawing.

In the accompanying drawing forming a part of this specification, wherein like reference characters indicate like parts:

Figure 1 is a top plan view of the leather working tool embodying my invention.

Figure 2 is an edge elevation, and

Figure 3 is a side elevation of the tool.

In the drawing wherein for the purpose of illustration is shown the preferred embodiment of my invention, the numeral 1 designates generally my improved leather working tool, the same comprising a substantially rectangular shaped metallic body 2 that is solid and that has formed at its inner end, a downwardly curved handle 3. The solid body 2 is formed with a transverse slot that extends through the opposite sides thereof, and the purpose of this slot will be presently described.

A substantially U-shaped yoke member denoted by the numeral 4 and formed from a single strip of flat metal has its crown portion spaced from the outer end of the solid body 2, the arms 5 of this yoke member being disposed against the respective sides of the body as clearly illustrated in Figure 1. The arms 5 are formed with the elongated registering slots that communicate with the slot

formed in the body 2. A laterally extending finger 6 is formed on the upper edge of the innermost arm at the free end thereof, and the purpose of this finger or ear will be 60 hereinafter more fully explained.

A gauge bar 7 is slidable through the slot formed in the solid bar 2 and also through the registering slots formed in the intermediate portions of the arms 5 of the yoke member 65 4, and the upper face of this gauge bar is provided with a conventional scale 8 as shown very clearly in Figure 1.

A vertically disposed cutting blade 9 is formed at its lower end with a laterally extending attaching flange 10 that is adapted to be secured to the inner end of the bar 7 in any appropriate manner such as is shown at 11 with reference more particularly to Figure 2 and the cutting edge of the blade faces 75 the handle portion 3 and is disposed at extreme inner end of the bar.

For the purpose of locking the slidable bar 7 in a fixed position so that the cutting blade 9 may be held in proper spaced relation with 80 respect to the inner side of the body 2, I provide a block 12 that is disposed between the outer end of the body 2 and the crown portion of the yoke 4 and a thumb screw 13 extends through a suitable opening in the crown 85 portion of the yoke and is threaded through an opening formed in the center of the block 12, the inner end of the thumb screw engaging the outer end of the body 2 and manifestly by turning the thumb screw in 90 one direction, said block 12 will cooperate with the yoke to effect a sliding movement thereof in an outward direction so that the slotted arms 5 of the yoke will engage the rear edge of the guide bar and force the forward edge of the bar into engagement with the forward edge of the slot formed in the body, and in this manner, the slidable bar 95 will be locked in its adjusted position.

The outer end of the gage bar 7 is formed 100 with a threaded opening to receive the externally threaded portion of a leather punch 14, said punch being formed at its upper end with a tool engaging head 15.

A leather creaser 16 is carried by the lower 105 end of the handle portion 3 for the purpose of creasing the strip of leather in the manner well known in the art.

A finger engaging hook 17 is secured to the bottom face of the rear portion of the body 110 2, as clearly illustrated in Figure 3.

In use, the thumb screw 13 is loosened to

permit the free sliding movement of the gage bar 7 with respect to the solid body 2 whereby the blade 9 may be moved laterally with respect to the body in order to permit the proper width of the strip that is to be cut from the large piece of leather to be accurately measured and in this manner the scale 8 provides a means to readily ascertain the distance between the cutting edge of the blade 9 and the innermost arm 5 of the yoke 4. After the blade has been properly adjusted or spaced with respect to the body 2, the set screw 13 is tightened whereby to lock the gage bar in its adjusted position against sliding movement. The handle 3 is then grasped with one of the fingers of the operator being in engagement with the finger grip 17 and the tool is then drawn toward the person using the same, one edge of the leather being disposed against the inner arm 5 of the yoke 4 and the laterally extending finger or ear 6 will be disposed above the upper face of the leather to insure the proper positioning of the same. The cutting edge of the blade will then cut through the leather in this manner—a strip of any desired width may be cut from a large piece of leather. The creaser 16 may then be used for creasing the strip along its edge portion and the punch 14 is then utilized for the purpose of forming one or more holes in the strip.

It will thus be seen from the foregoing description, that I have provided a leather working tool which will at all times be positive and efficient in its operation, and due to its simplicity the blade carrying bar can be readily and easily adjusted to cut strips of leather of various widths.

While I have shown the preferred embodiment of my invention, it is to be understood that various changes in the size, shape and arrangement of parts may be resorted to without departing from the spirit of the invention and the scope of the appended claims.

Having thus described the invention, what I claim as new is:—

1. In a tool of the class described, a solid body formed with a transverse through slot, a rearwardly extending handle at one end of

the body, a flat gage bar slidable through the slot in the body, a vertically disposed cutting blade carried by one end of the bar, means for securing the slidable bar in any adjusted position, said last mentioned means comprising a yoke, the arms of which are disposed against the sides of the body, said arms being formed with registering slots that communicate with the slot in the body and through which the bar is slidable, a block disposed between the outer end of the body and the crown portion of the yoke, a screw extending through the crown portion of the yoke and the block and adapted to engage the outer end of the body for the forcing of the yoke outwardly to lock the bar against sliding movement, and a laterally extending ear formed on the upper edge of the innermost arm of the yoke at the free end thereof to prevent upward movement of the work while the tool is in use.

2. In a leather cutting tool of the class described, a solid body, a downwardly curved handle formed on the rear end of the body, said body being provided with a transverse through slot, a substantially U-shaped yoke, the crown portion thereof being spaced from the outer end of the body, the arms of the yoke being disposed against the respective sides of the body and formed with slots that register with the slot in the body, a flat gage bar slidable through the communicating slots, a vertically disposed cutting blade carried by one end of the gage bar, a block arranged within the yoke between the outer end of the body and the crown portion of the yoke, a screw extending through the crown portion of the yoke and the block and adapted to engage the outer end of the body for moving the yoke outwardly to lock the bar against sliding movement in any adjusted position, and a laterally extending ear formed on the upper edge of the innermost arm of the yoke at the free end thereof to prevent upward movement of the leather during the cutting of the same.

In testimony whereof I affix my signature.

JOSEPH H. DORVAL.
